UNITED STATES PATENT OFFICE.

ROBERT B. BARBER, OF HAZLETON, PENNSYLVANIA.

TANK-FILLING VALVE.

1,219,690.

Specification of Letters Patent. Patented Mar. 20, 1917.

Application filed June 8, 1916. Serial No. 102,542.

To all whom it may concern:

Be it known that I, ROBERT B. BARBER, a citizen of the United States, residing at Hazleton, in the county of Luzerne and State of Pennsylvania, have invented certain new and useful Improvements in Tank-Filling Valves; and I do declare the following to be a full, clear, and exact description of the invention, such as will enable others skilled in the art to which it appertains to make and use the same.

My invention relates to improvements in valves of the type adapted to automatically open when tanks are emptied of water to permit refilling thereof, and to automatically close when the water or other fluid has risen in the tank to a predetermined level, the device being adapted primarily for use on flushing tanks.

The object of the invention is to provide an extremely simple and highly efficient valve of the class specified which will be held in closed position by the water pressure and will have no loose or moving joints whatever through which the water may leak.

With this general object in view, the invention resides in certain novel features of construction to be hereinafter fully described and claimed, the descriptive matter being supplemented by the accompanying drawing which constitutes a part of this application, and in which:

Figure 1 is a sectional view of a flushing tank showing the improved valve applied; Fig. 2 is an enlarged vertical section of the valve showing the same closed;

Fig. 3 is a similar view of the valve opened;

Fig. 4 is an edge view;

Fig. 5 is an enlarged sectional detail of the valve proper and its stem and seat; and

Fig. 6 is an elevation of said valve proper.

In specifically describing the structure shown in the drawing above briefly described, similar characters will be employed to designate corresponding parts throughout the several views and reference will be herein made to the numerous elements by their respective indices. To this end, the numeral 1 designates a vertically disposed tubular inlet stem having at its lower end a stop collar 2 to bear on the bottom of a tank 3, said stem being enlarged and externally threaded below said collar as indicated at 4 to facilitate the attachment of the water supply pipe 5. The upper end of the stem 1 is

provided with an enlarged integral head 6 here shown of cylindrical formation and as disposed on a horizontal axis. One end of said head projects a suitable distance beyond the stem 1 and is closed by a screw cap 7 which rotates on the axis of the head, a gasket 8 being provided to form a tight joint. Head 6 and cap 7 form an outer chamber communicating with stem 1.

Formed integrally with the upper end of stem 1 on the side thereof opposed to the projecting end of said head 6, is a vertical water discharge neck 9, the upper end of said neck and said stem being in communication through the instrumentality of a port 10 disposed in line with the axis of the head, said head having in its outer side an opening 11 disposed on said axis. A tube or inner chamber 12 is threaded into the enlarged inner end of the port 10 and extends therefrom into the head 6, the free end of said tube being rounded as indicated at 13, whereby it constitutes an effective valve seat (see Fig. 5).

A horizontal valve stem 14 passes through the opening 11, the port 10, and the tube 12, the inner end of said stem carrying a valve 15 coöperating with the seat 13. The valve 15 includes an imperforate nut 16 threaded on the inner end of the stem 14, a packing disk 17 of suitable composition being clamped between said disk and a collar 18 which is formed integrally with the stem 14. To prevent the edge of the disk 17 from warping and to thereby always hold said disk in proper position for effective engagement with the seat 13, a ring 19 is threaded on the nut 16 as shown clearly in Figs. 5 and 6, one side of said ring having an internal annular flange 20 which clamps the edge of the disk between itself and the nut 16. The periphery of ring 19 has formed thereon a plurality of projections 21 which are adapted to slidably contact with the interior of the head 6 to guide the valve in its movement and at the same time to sufficiently space it from said head to permit the passage of water around said valve.

One or more lugs 22 may be formed integrally with and project laterally from the upper end of the neck 9 above the opening 11, two of said lugs being here shown, and the lower end of a lever 23 is fulcrumed between said lugs as indicated at 24, the lower end of said lever having a suitably shaped head 25 which is received in a slot

26 in an ear 27, said ear projecting horizontally from a nut 28 threaded on the outer end of stem 14. The upper end of lever 23 is in the form of a disk 29 having 5 teeth 30 which engage similar teeth on a second disk 31, the two being clamped together by a set screw or the like 32. The edge of the disk 31 has formed integrally therewith a sleeve 33 in which the stem 34 10 of a float 35 is adjustably secured by means of a set screw 36. The disks 29 and 31 with their coöperating teeth and the set screw 32, permit the float stem 34 to be so adjusted as to cause the valve to cut off the water 15 supply at any desired level.

Preferably employed in connection with the features above described, is a screw plug 38 which normally closes an opening 39 in the upper end of the neck 9, this arrangement being provided in order that by removing said screw, a tube may be tapped into the opening 39 to supply an after flow 20 of water to a closet bowl to refill the hopper thereof after flushing.

25 By constructing the improved valve in the manner shown and described, it will be not only simple and inexpensive, but will be highly efficient and durable, particular emphasis being laid upon the fact that no loose 30 or moving joints exist through which water may leak, it being evident that when the valve 15 is closed, the water will be trapped in the head 6 and will exert its pressure against said valve to hold the latter seated. 35 This pressure also assists the float 35 in closing the valve, as will be obvious.

In use, the device will be installed as shown in Fig. 1 and the tank being normally full, the float 35 will be elevated with 40 the result that the valve 15 is closed, being held in this position by the water pressure as above stated. When, however, water is discharged from the tank 3, the float 35 will lower, thus causing the parts operated there- 45 by to open valve 15 to again permit the device to supply water to the tank to refill the same (see Fig. 3).

In the foregoing, I have described certain specific details for illustrative purposes, and 50 in the accompanying drawings the same have been shown, but it is to be understood

that within the scope of the invention as claimed, numerous changes may be made without sacrificing the main advantages thereof. It will also be understood that the 55 invention may be embodied in other than float controlled valve devices.

I claim:

A tank filling valve comprising a tubular one piece vertical inlet stem having a hollow horizontally disposed cylindrical head formed integrally with its upper end, said head being closed at one end by a removable screw cap and having a horizontal port leading from its other end in line with the 60 axis of the head, a vertical outlet neck into the upper end of which said port discharges, said neck being formed integrally with the inlet stem and having an opening in horizontal alignment with said port, a 65 pair of lugs formed integrally with the upper end of said neck and projecting therefrom above said opening, a short horizontal tube threaded in the aforesaid port and extending into the hollow head, the free end 70 of said tube being disposed in a vertical plane to form a valve seat, a valve in the head having projections slideable on the curved wall thereof and having a flat gas- 75 ket for contact with said valve seat, a valve 80 stem extending horizontally from said valve through the port and the aforesaid opening, a nut threaded on the outer end of said valve stem and having an integral hori- 85 zontally extending ear at its upper edge 90 underlying the aforesaid lugs, said ear having a slot opening through its upper and lower sides, a vertically disposed lever ful- 95 crumed between its ends between said ears and having an elongated head on its lower end received in the slot of said ear, said head having rounded ends for contact with the ends of the slot, a float stem extending laterally from the upper end of the lever, and a float on said stem.

In testimony whereof I have hereunto set my hand in the presence of two subscribing witnesses.

ROBERT B. BARBER.
